[57] CLAIM

The ornamental design for a van extension module, as shown and described.

DESCRIPTION

FIG. 1 is a perspective view of a van extension module showing my new design, it being understood that the broken lines are for illustrative purposes only;

FIG. 2 is a top plan view thereof;

FIG. 3 is an elevational view of the rear exterior thereof;

FIG. 4 is an elevational view of the front interior thereof;

FIG. 5 is a bottom plan view thereof;

FIG. 6 is a side elevational view thereof; and

FIG. 7 is a side elevational view thereof opposite to that shown in FIG. 6.
